UNITED STATES PATENT OFFICE.

LEE W. ANDREWS, OF LIVE OAK, CALIFORNIA.

STEAM-ENGINE GOVERNOR.

SPECIFICATION forming part of Letters Patent No. 256,946, dated April 25, 1882.

Application filed December 19, 1881. (No model.)

To all whom it may concern:

Be it known that I, LEE W. ANDREWS, of Live Oak, county of Sutter, State of California, have invented a Governor for Steam-Engines; 5 and I hereby declare the following to be a full, clear, and exact description thereof.

My invention relates to an improved mechanism for governing the admission of steam, vapor, gas, or air under pressure to the cylinders of engines; and it consists of a two-part cylindrical valve, constructed substantially as shown and described, reciprocating in a cylinder so as to alternately expose and cover ports which open through the sides of the cylinder. 10 The two parts of the valve close against seats at the center, and are caused to close against these seats by springs acting against their outer ends. A rod which is caused to reciprocate by connection from the engine-shaft passes 15 longitudinally through both parts of the valve, and another rod, which also passes through both parts of the valve, is connected with an oscillating balance-wheel having a coiled spring similar to that shown in my patent of September 20, 1881. The first rod has a collar fixed 20 to it midway between the cross-bars which extend across each part of the valve, and pawls which are hinged to the inner sides of these cross-bars engage this collar at each end, so 25 that when the engine moves slowly the two parts of the valve move simultaneously, each moving the full stroke without cut-off. The second rod has two arms secured to it and projecting up beside the first so that their ends 30 are just beneath the pawls before mentioned. When the engine runs faster than the oscillation of the balance-wheel these arms engage the pawls so as to lift them alternately clear of the collar, when the exterior springs will 35 close each part of the valve as it is released, and thus cut off the supply of steam to the cylinder.

Referring to the accompanying drawings, Figure 1 is a longitudinal section. Fig. 2 is a transverse section. Fig. 3 is a modification. 45

A is the engine-cylinder. B is the valve-chamber, above or at one side of which is the cylinder C, within which the two parts D D' of the hollow cylindrical valve move. Each 50 valve has a cross-bar, d, and the meeting ends of the valves are fitted to close against each

other or against a seat, a, as shown, and prevent steam which is admitted in the direction of the arrow from entering the passages G, leading to the cylinder. The outer ends of these 55 valves are made larger than the body, forming flanges b, which fit in enlarged parts of the cylinder, and when the valves are closed against their seats by the action of the springs E a quantity of air between each flange b and the 60 shoulders c at the termination of the enlarged portions of the cylinder acts as a cushion to prevent the valve striking too forcibly upon its seat. The valves are moved by a rod, F, which enters the case through a stuffing-box, 65 and is driven by levers and connections from the engine-shaft. This rod passes loosely through the cross-bars d of the valves, and has a collar or enlargement, e, midway between the bars d. Pawls i are hinged to the inner sides of 70 the bars, near the top, so that their inner or free ends will just fit against the ends of the collar e, and thus cause the two parts of the valve to move simultaneously. This alternately opens and closes the passages G, by which steam is 75 admitted to the steam-chest B.

In order to close the valves more rapidly, and thus cut off the supply of steam, I employ a balance-wheel, H, having a coiled spring around it and connecting it with the side of 80 the case like the balance-wheel of a watch. A connecting-rod, I, unites a crank-pin upon the wheel with a rod, J, which passes loosely through the bars d just below the rod F. This lower rod has two arms, K K, secured to it so 85 as to project upward at each end of the collar e and a short distance from it, so that the reciprocation of the rod F causes the collar to strike the arms, and by this means the arm J operates the balance-wheel and makes it 90 reciprocate. The upper ends of the arms K are beveled, and the pawls i have inclines formed upon their lower sides near the ends which engage the collar e, so that as the ends of the arms K pass beneath the pawls they raise them 95 up clear of the collar e, and this allows the springs E at the ends to act so that one valve being opened by the movement of the rod F, is kept open until the pawl i on that side is tripped by the arm K, when it is closed at once by its spring. Whenever the engine runs faster than the vibration of the balance-wheel it will 100

be seen that the pawls will be tripped more quickly, because the rod F moves faster than the rod J, and the inclines upon the pawls *i* are more quickly brought into contact with the 5 arms K, by which they are tripped so as to allow the valves to close.

Having thus described my invention, what I claim as new, and desire to secure by Letters Patent, is—

- 10 1. The valves D D', reciprocating within a case and caused to close against central seats by springs E, in combination with the valve-stem F, having the central collar, *e*, the hinged pawls *i*, acting against the ends of this collar, and the arms K, whereby the valves are alternately opened, substantially as herein described.
- 15 2. The valves D D', reciprocating in a case and having the pawls *i* resting against the ends of the collar *e* upon the reciprocating valve-stem F, and spring E, in combination with the 20 arms K, secured to the rod J, which is recipro-

cated by the action of the balance-wheel H, said arms tripping the pawls and allowing the valves to close, substantially as herein described.

25

3. The valves D D', reciprocated in a case, A, by the valve-stem F, and collar *e*, pawls *i*, and springs E, and having the seats *a*, said valves having flanges *b* to inclose an air-cushion between themselves and the shoulder *c* of the 30 cylinder, substantially as herein described.

4. In a governor for engines, a releasing mechanism constructed substantially as shown and described, and adapted to be operated by the isochronal vibrations of the pendulum or 35 balance-wheel H, substantially as herein described.

In witness whereof I hereunto set my hand.

LEE W. ANDREWS.
